UNITED STATES PATENT OFFICE.

ARTHUR E. DE SAVE, OF MOBILE, ALABAMA.

CROW'S-NEST FOR SHIPS.

1,354,383.

Specification of Letters Patent. Patented Sept. 28, 1920.

Application filed March 22, 1918. Serial No. 223,961.

To all whom it may concern:

Be it known that I, ARTHUR E. DE SAVE, a citizen of Great Britain and Ireland, resident of Mobile, Mobile county, Alabama, 5 have invented a new and Improved Crow's-Nest for Ships, of which the following is a full, clear, and exact description.

My invention has for its object to provide a crow's-nest which is inclosed to afford 10 protection for the lookout and which is supported by a universal joint on a boom which extends from a mast on a ship.

Additional objects of the invention will appear in the following specification in 15 which the preferred form of my invention is described.

In the drawings similar reference characters refer to similar parts in all the views, in which—

20 Figure 1 is a view illustrating the manner in which my invention is used.

Fig. 2 is an enlarged view illustrating the crow's-nest and the means which are employed for securing it to a mast.

25 Fig. 3 is a sectional plan view of Fig. 2.

Fig. 4 is a sectional view of Fig. 2 through the crow's-nest and looking in the direction of the mast, and

30 Fig. 5 is a sectional view on the line 5—5 of Fig. 4.

By referring to the drawings, it will be seen that the ship is provided with a mast 10 and that straps 11 and 12 are bolted to the mast; the strap 12 being disposed at a 15 distance above the strap 11. Secured to the strap 11, there is a block 13 and extending at the sides of the strap 11, there are arms 14. Beams 15 are provided having a set of ends 16 which are disposed at the sides to 20 the block 13, the ends 16 of the beams being held in position relatively to the block 13 by means of bolts 17. The other set of ends 18 of the beams are disposed against the sides of a member 19 of a universal joint 20; 25 the ends 18 of the beams 15 being secured to this universal joint member 19. The universal joint 20 has another member 21 which is secured to the top 22 of the crow's-nest 23.

It will be seen that with this construction, 30 the crow's-nest 23 will at all times be held with its bottom 24 and with its top 22 in a horizontal position, so that the work of the lookouts stationed within the crow's-nest may not be interfered with by the rolling 35 and pitching of the ship.

Braces 26 are bolted to the arms 14, the braces 26 converging forwardly and being bolted to the beam 15 at 27. Additional supports for the beams 15 consist of members 28 which are bolted to the strap 12 and to the beams 15 adjacent the universal joint. 60

In the bottom 24 of the crow's-nest 23 there is a trap-door 29 which is normally closed but which may be opened to afford 65 communication with the deck when desired. There is also a hatch 30 at the top 22 of the crow's-nest through which entrance may be made. The crow's-nest is preferably provided with two periscopes 31, one disposed on each side, each of these periscopes being 70 provided with means 32 by which it may be rotated. Should the crow's-nest be used without the periscopes 31, the watch may keep a most efficient lookout through the windows 33 in the sides of the crow's-nest, 75 the watch having a larger vision than in the ordinary crow's-nests which are now being used.

The crow's-nest may be provided with 80 telegraph, or other means for communicating with the bridge and gun crews and it may also be provided with an electric heater for winter and with fans for summer, so that at all seasons of the year the crow's-nest may be made as comfortable as possible. 85 The crow's-nest may be reached from the beams 15 and is provided with a foot board 34 with a hand rail 35. As illustrated in Fig. 5 of the drawings, the hatch may be opened and closed by means of a lever 36, 90 entrance being afforded to the crow's-nest when the said hatch is opened.

The crow's-nest is supported on the beam 15 by a universal joint as has been described, and this will retain the crow's-nest 95 in a perpendicular position at all times and irrespective of any pitching and rolling motion of the ship, as this pitching and rolling motion will be taken up by the universal joint. The only motion of the crow's-nest 100 will be a vertical motion. As the lookout in the crow's-nest is protected from the weather and is made comfortable, it is possible for him to keep a better lookout for a longer period of time and without eye strain 105 than is the case under the present conditions.

The crow's-nest may be reached by a foot board 40 which is supported on the beam 15 by brackets 42, the foot board 40 extending 110

from the mast 10 to a point from the crow's-nest. The foot board 40 is provided with a hand rail 41 which extends from the mast to the outer end of the foot board, the hand rail 41 being fastened to the beam 15.

What I claim as new and desire to secure by Letters Patent is:

In combination with a ship having a mast, a universal joint having two members, a

block secured to the mast, two beams having one set of ends disposed at the sides of and secured to the block and their other set of ends disposed at the sides of a member of the universal joint and secured thereto, and a crow's-nest secured to the other member of the universal joint.

A. E. DE SAVE.
